UNITED STATES PATENT OFFICE.

FRED BOWMAN AND EDWARD ELLIS, OF CUSHING, OKLAHOMA.

FURNITURE.

Application filed April 21, 1926. Serial No. 103,534.

It is the purpose of the present invention to provide an improved article of furniture which will combine the advantages of a kitchen cabinet, a refrigerator, and a water cooler, the construction providing a convenient, attractive and useful article of furniture.

Another object of the invention is the provision of an article of furniture which will include in compact form, a relatively large number of commodious compartments, novel means being provided for rotatably mounting the article so that each of the compartments may be conveniently reached.

With the above and other objects in view, the invention further includes the following novel features and details of construction, to be hereinafter more fully described, illustrated in the accompanying drawings and pointed out in the appended claim.

In the drawings:—

Figure 1 is an elevation of the invention. Figure 2 is a section on the line 2—2 of Figure 1.

Figure 3 is a similar view on the line 3—3 of Figure 1.

Figure 4 is a section taken substantially on the line 4—4 of Figure 2.

Figure 5 is a section on the line 5—5 of Figure 2.

Figure 6 is a section on the line 6—6 of Figure 2.

Referring in detail to the drawings, wherein like characters of reference denote corresponding parts, the invention as shown, comprises a casing which includes an upper section 10 and a lower section 11. These sections each include a bottom 12 and a top 13, the top of the lower section and the bottom of the upper section being bolted or otherwise secured together by means of bolts 14, so that the two sections will form a single unit. The top of the lower section and the bottom of the upper section form a horizontal partition which divides the casing and this partition is provided with a recess 15 which accommodates a slide 16, the latter being useful as a dough board, or for other purposes.

The casing or cabinet is supported upon a bearing standard 17 which extends through the bottom of the lower section 11 and is connected with a platform 18. The upper end of the standard 17 supports the cabinet by means of an anti-friction bearing 19

which is interposed between the upper end of the standard and the top of the lower section. The standard 17 is constructed so that the bottom of the lower section will be spaced above the platform 18 and in order to prevent tilting action of the cabinet, the lower section carries anti-friction rollers 20 which are interposed between said section and the platform 18.

Both sections are provided with vertically disposed partitions 21. These partitions divide the lower section into an inner compartment 22 and outer compartments 23 which surround the inner compartment. The partitions 21 of the upper section divide this section into an inner compartment and outer surrounding compartments, the latter being indicated at 24. The inner compartment of the upper section is divided into an ice chamber 25, a water cooler 26 and a compartment 27, the latter being designed to receive drinking glasses and the like. The cooler 26 is provided with a spigot 28.

The ice compartment 25 is provided with a door 29 which is hinged as indicated at 30 at its lower edge to the lower portion of the ice compartment. This door opens downwardly into one of the compartments 24 and is provided upon its inner face with ice guides 31 so that the ice may be conveniently slid into the chamber 25. The compartments 23 and 24 may be provided with horizontally arranged shelves 32 and if desired, these shelves may be removable and adjustable as to their height.

The ice chamber 25 is in communication with one end of a drain pipe 33 and the lower end 34 of this pipe extends into one of the compartments 23 of the lower section and into a pan 35 which is removably positioned in said compartment. The ice chamber may be provided with an additional slide bar 36 and a vent opening 37.

The cabinet may be of suitable configuration, but it is preferred to make it of hexagonal cross sectional shape and each of the compartments 23 and 24 are provided with doors. The doors of the compartments 24 may be provided with glass panels 38 and the doors of the lower section 10 may be provided with wood or other panels 39.

The invention is susceptible of various changes in its form, proportions and minor details of construction and the right is here-

in reserved to make such changes as properly fall within the scope of the appended claim.

Having described the invention what is claimed is:—

An article of furniture comprising a casing, a partition dividing the casing into an upper section and a lower section, vertical partitions dividing each section into 10 separate compartments including an inner central compartment and outer compartments surrounding the inner compartment, an ice chamber in the inner compartment of

the upper section, a pan within one of the compartments of the lower section, a drain pipe extending from the ice chamber into the pan, a door for each compartment, a vertical swinging door having its lower edge hingedly secured at the bottom of the ice chamber and opening outwardly into one 15 of the compartments and ice guides carried upon the inner face of the door.

In testimony whereof we affix our signatures.

FRED BOWMAN.
EDWARD ELLIS.
